(57) **CLAIM**

The ornamental design for an electronic locker lock, as shown and described.

DESCRIPTION

FIG. 1 is a front right perspective view of an electronic locker lock showing our new design;

FIG. 2 is a top plan view thereof;

FIG. 3 is a left side elevational view thereof;

FIG. 4 is a front elevational plan view thereof;

FIG. 5 is a right side elevational view thereof; and,

FIG. 6 is a bottom plan view thereof.

The broken lines environment is for illustrative purpose only and forms no part of the claimed design.
